UNITED STATES PATENT OFFICE.

DANIEL F. CALHANE, OF WORCESTER, MASSACHUSETTS.

ELECTRIC CRUCIBLE-FURNACE.

1,091,808.

Patented Mar. 31, 1914.

Application filed November 3, 1911. Serial No. 658,300.

To all whom it may concern:

Be it known that I, DANIEL F. CALHANE, a citizen of the United States, residing at Worcester, in the county of Worcester and 5 State of Massachusetts, have invented a new and useful Electric Crucible-Furnace, of which the following is a specification.

This invention relates to an electric furnace suitable for very high temperatures.

10 The principal objects of the invention are to provide a convenient and inexpensive construction for this purpose in which the heat shall be concentrated along the walls of the crucible by forcing the current to flow in a 15 restricted path therealong so as to increase the efficiency and the practicable limit of the working temperature; to provide means whereby this concentration can be caused to take place at any desired plane along the 20 wall of the crucible and throughout any desired zone thereof; to provide a construction in which the current shall be caused to flow along the crucible walls without unduly heating the bottom; to provide for adjusting 25 the support of the crucible and said concentrating means so that crucibles of different sizes can be used without altering the furnace; to employ an improved refractory material as the crucible support and means 30 for concentrating the heat as set forth above; to provide improvements in efficiency of heat insulation; and to provide an improved form of concentric sets of crucibles nested together so that the furnace can 35 be continuously operated for melting the charges of a plurality of crucibles without disturbing the carbon core of the furnace and without allowing it to cool down.

Further objects and advantages of the invention will appear hereinafter.

Reference is to be had to the accompanying drawings in which—

Figure 1 is a vertical central sectional view of a preferred form of crucible furnace constructed in accordance with this invention, and Fig. 2 is a similar view of a modified form.

In the form shown in Fig. 1 the furnace is 45 constructed with an exterior cement wall 10 inside which is an asbestos filling 11 separated into an outer and inner member by a layer of asbestos boards 12. On the inside of these is a clay wall 13. These parts preferably are substantially cylindrical in form 50 but that of course is not material. The efficiency in heat insulation of the successive

walls of asbestos packing inside the concrete walls is one advantage of this invention. The space inside the clay wall is provided with a cement block 14 to form the bottom 60 thereof. Above this block is a carbon core 15 preferably formed of powdered carbon and constituting a packing for the crucible and a resistor for the current. At the bottom of this core is an annular graphite electrode 16. This is connected with a source of current through a circular terminal 17 or the like, shown as having a central hub and radial spokes. Inside the annular electrode is a block 18 of insulating material, (alum- 65 dum). This block is shown as comprising a plurality of independently removable parts of different heights superimposed one on the other so that any desired part can be used to support the bottom of the crucible 70 19 and bring its bottom to different heights above the bottom of the furnace. By this means the furnace can be used to accommodate crucibles of different sizes. The separate blocks of which this support is made 75 80 up preferably have mortises and tenons formed at their ends so that they can easily be piled up vertically. At the top of the carbon packing another circular graphite electrode 20 is located similar to the electrode 17. This is preferably annular in form also. The electrodes are of graphite chiefly because it is more easily machined than other forms of carbon. This furnace is provided with a clay cover 21 as usual. 85 90

Located in the carbon core or packing are a series of insulating rings 23 each of annular form and arranged to substantially fill the space between the crucible and the clay wall 13. By means of these rings the 95 current is forced to be concentrated in a small space along the walls of the crucible and consequently tends to heat this space higher than it would if diffused throughout the space between the clay walls 13. At the 100 same time it causes all this heat to be utilized for the purpose of raising the temperature of the crucible and melting its contents. In this way the efficiency of the device is very greatly increased. In addition 105 to this by having these rings substantially in a "floating" condition; that is at any point within the carbon core 15, it is obvious that the plane of concentration of the heat can be located either high or low on the 110 crucible. If the crucible contains only a small charge to be melted; obviously this

ring or rings will be located near the bottom. In addition to this feature, it will be observed that this insulating zone is made up of a plurality of thin rings which can be removed and replaced at will so that the extent of the concentrated zone can be increased or decreased as desired. In this way a maximum efficiency is secured. It will be observed that the adjustability of the support for the crucible co-operates with the adjustability of the insulating rings 23 to permit crucibles of different sizes to be used in a single furnace. I have found in practice that for the high temperatures for which this furnace is designed, alundum is the best material for these rings as it is also for the blocks or support 18. Alundum of course, as is understood, is an artificial corundum, oxid of aluminum. By the use of alundum for these purposes both a support for the crucible and a deflector for the heat are secured which are of suitable construction, not liable to become friable at the surface after repeated heatings to its melting point, and at the same time they are of a material having a melting point well above that required for ordinary operations in a furnace of this kind. I find in practice moreover, that the crucible can be heated to the temperature of melting of alundum without greatly damaging the alundum insulating rings 23 or the blocks 18. This is due to the fact that the intense heat zone is mainly between the walls of the crucible and the rings. The alundum rings preferably are spaced in the vicinity of a quarter of an inch from the crucible. The crucible preferably is pressed alundum containing a minimum of clay. This furnishes insulation within the heated zone and prevents the loss of efficiency by the diversion of the current through the crucible walls.

Another feature of the invention consists in the provision of a nest of crucibles. In this case the crucible 19 is shown as of ordinary form but within it is located a second alundum crucible 25 having a shoulder 26 resting on the top of the crucible 19 and otherwise fitting its interior with any desired degree of nicety. When the charge in the crucible 25 has been melted the cover 21 can be removed and this crucible taken out, leaving the crucible 19 already heated to a high temperature and ready to receive a charge. In this way the furnace can be used for a plurality of charges without disturbing the carbon core and without allowing the furnace to cool down to any appreciable extent. In this way the heat is retained and the efficiency increased. At the same time another advantage is secured by reason of the fact that there is practically only a single handling of the crucibles in introducing them into the furnace. This also results in an additional saving of time.

The crucible 25 is shown as being provided with a lining 27 of magnesia.

In the form shown in Fig. 2 the arrangement is somewhat simpler as the external walls of the furnace are made of a plurality of fire bricks 30. Inside this is a body 31 of Portland cement, magnesia oxid and asbestos, forming the sides and bottom. Inside this is a fire clay muffle 32, iron bound. The alundum blocks 18 are used as in Fig. 1. The two electrodes are graphite rings 33 and 34. The core 35 is made as in Fig. 1, and a concentrating insulating ring 23 is shown formed of alundum. Obviously this ring is separated from the crucible by conducting material to permit the current to flow between them and to be concentrated along the wall of the crucible adjacent to the ring. In this case a graphite crucible 36 is shown as having an alundum lining 37 to keep the melts from carbon contamination.

In actual use it is believed that this furnace has been raised to a temperature of about 2800 degrees centigrade. It has at least been up to a point high enough to fuse alundum.

Although I have illustrated and described two preferred forms of the invention, I am aware that other modifications can be made therein without departing from the scope of the invention as expressed in the claims. Therefore, I do not wish to be limited to all the details of construction shown and described, but

What I do claim is:—

1. As an article of manufacture, a crucible furnace having an exterior cement wall, a wall inside the same of asbestos filling having a partition of asbestos board intermediate between its outer and inner surfaces, an inner wall of solid insulating material, a cement bottom inside the inner wall, an electrode on the cement bottom, and an electrode at the top of the furnace.

2. As an article of manufacture, a crucible furnace having insulating containing walls, an electrode at the bottom of the furnace and one at the top, a plurality of removable and replaceable solid insulating blocks superimposed one upon the other at the bottom of the furnace for supporting a crucible, a continuous granular packing around the blocks and crucible, and a plurality of independently removable insulating rings located one above the other surrounding the crucible, whereby the height of the crucible can be adjusted by removing and replacing the blocks and the zone of the crucible effected by the insulating rings can be regulated by removing and replacing the rings.

3. As an article of manufacture, a crucible furnace having insulating containing walls, means for supporting a crucible therein at different heights relative to said walls,

a resistor for receiving the crucible and conducting the current and a plurality of independently removable insulating rings located in said resistor and extending substantially to the walls of the crucible for concentrating the current and heat along any desired portion thereof vertically.

4. As an article of manufacture, a crucible furnace having insulating containing walls, means for supporting a crucible, a resistor for receiving the crucible and conducting the current, and a plurality of independently removable insulating rings located in said resistor and extending substantially to the walls of the crucible for concentrating the current and heat along any desired zone thereof.

5. In a crucible furnace, the combination of insulating containing walls, an electrode 20 at the bottom, removable and replaceable

blocks of alundum superimposed at the bottom, a crucible on said blocks, a continuous carbon packing around the blocks and crucible, a plurality of separately removable alundum rings located within said packing 25 for directing the current and concentrating the heat along the walls, and a second electrode in contact with the carbon packing.

6. As an article of manufacture, an electric furnace comprising electrodes, and a refractory conductor between them having a ring of alundum located therein.

In testimony whereof I have hereunto set my hand, in the presence of two subscribing witnesses.

DANIEL F. CALHANE.
